(57) **CLAIM**

The ornamental design for connector housing, as shown and described.

DESCRIPTION

FIG. 1 is a perspective view of an embodiment of a connector housing showing our new design;

FIG. 2 is a top plan side view thereof;

FIG. 3 is a bottom plan view thereof;

FIG. 4 is a front elevational view thereof;

FIG. 5 is a rear elevation view thereof;

FIG. 6 is a left side elevational view thereof; and,

FIG. 7 is a right side elevational view thereof.

The broken lines in the drawings illustrate portions of the article and form no part of the claimed design.

1 Claim, 5 Drawing Sheets
